UNITED STATES PATENT OFFICE

146,731

DESIGN FOR A POKER CHIP HOLDER

Raymond Vaccarello, Los Angeles, Calif., assignor of one-half to Sam Vaccarello, Los Angeles, Calif.

Application February 19, 1946, Serial No. 126,719

Term of patent 14 years

(Cl. D34—5)

To all whom it may concern:

Be it known that I, Raymond Vaccarello, a citizen of the United States of America, residing in the city of Los Angeles, in the county of Los Angeles, State of California, have invented a new, original, and ornamental Design for a Poker Chip Holder, of which the following is a specification, reference being had to the accompanying drawings, forming a part thereof.

Fig. 1 is a perspective view of a poker chip holder showing my new design;

Fig. 2 is a top plan view thereof;

Fig. 3 is a side elevational view thereof; and

Fig. 4 is an end elevational view thereof.

I claim:

The ornamental design for a poker chip holder, substantially as shown.

RAYMOND VACCARELLO.
